UNITED STATES PATENT OFFICE.

FRANCIS LYST, OF LONDON, ENGLAND.

FIRE-ESCAPE, HOIST, &c.

SPECIFICATION forming part of Letters Patent No. 582,753, dated May 18, 1897.

Application filed February 4, 1896. Serial No. 577,987. (No model.) Patented in England April 20, 1895, No. 7,911.

To all whom it may concern:

Be it known that I, FRANCIS LYST, a subject of the Queen of Great Britain and Ireland, and a resident of 64 Somerville Road, 5 Hatcham, London, in the county of Surrey, England, have invented certain new and useful Improvements in Fire-Escapes, Hoists, and Such Like, (for which I have obtained a patent in Great Britain, No. 7,911, bearing 10 date April 20, 1895,) of which the following is a specification.

This invention refers to portable elevators or extensible fire-escapes for saving life at fires and for like purposes.

15 It consists of a combination of three distinct parts—namely, a carriage with appliances for tilting same, a drum with a coiling ladder and appliances for coiling and uncoiling same, and a series of crossed extending 20 lazy-tongs pivoted at their centers and each pair pivotally connected at their ends to the pair below and above them, with appliances for operating same.

I will now describe the invention with reference to the accompanying drawings, in which—

Figure 1 shows a perspective view of my invention mounted upon a hand truck or cart, the rope ladder and coiling-drum being omitted. Fig. 2 shows a side elevation of same. The ladder is indicated by two dotted lines. The drum on which the ladder is wound is also shown. Fig. 3 shows a plan view of Fig. 2. Fig. 4 shows a detail side view of the 35 mechanism for keeping the platform at the upper end of the lazy-tongs rigid and straight. Fig. 5 shows a front elevation of Fig. 4. In both Figs. 4 and 5 the top of the ladder is shown. Fig. 6 shows a plan and side view of the 40 preferable method of pivoting or connecting the lazy-tongs where they cross each other. Fig. 7 shows a side and end view of the form of combined traveling nut and socket I use for expanding and contracting the lazy-tongs by 45 means of a right and left handed screw-thread. Fig. 8 shows a plan view of my invention in the closed position applied to a four-wheeled wagon. Fig. 9 shows a perspective view of Fig. 8 in the partially-raised position. In this 50 and the previous figure the lazy-tongs are indicated by means of plain dotted lines. Also, the arrangement for tilting the frame carry-

ing the lazy-tongs is different from that previously shown, consisting, as it does, of a secondary set of lazy-tongs similar to but smaller than those already shown. Fig. 10 shows a detail half-plan view of the method of employing coiled springs to assist in the raising of the escape.

a, Figs. 1, 2, and 3, is the foundation platform or frame to which the wheels and axle are connected.

b is a secondary tilting support or frame on which the lazy-tongs and their fittings are mounted. This frame b is attached to the 65 platform a by means of hinges a' or other suitable means to allow same to be tilted to any angle required by means of the rack-and-pinion gear, as shown in Fig. 1.

c is a vertical toothed rack which is attached to an extension-piece of the frame b. This rack c engages with a toothed pinion c', mounted upon a small counter-shaft c², supported by suitable bearings c⁴. This shaft can be rotated in any suitable manner at either 70 end by means of a hand-wheel or crank-handle c⁶, thus tilting the frame b as desired. Further, upon the shaft c² is mounted a loose-running tension-roller c⁵, round which the rope ladder passes when being wound or un- 75 wound off its coiling-drum.

Referring now to the means for raising and lowering the lazy-tongs, d d are plumber-blocks for supporting the right and left handed square-threaded screw e, rotated by 80 crank-handles e² e³.

e' e' are traveling nuts working on the screw e. Attached to these nuts e' are sockets which receive the ends of the lower pair of lazy-tongs f. This combined nut and socket is 85 shown in detail in Fig. 7.

f' f' are joints where the lazy-tongs f cross in their centers and join at their ends, and are shown in detail in Fig. 6.

g is a cross-head (shown in detail in Figs. 95 4 and 5) at the upper end and forming the head of the lazy-tongs f, which head is kept straight and rigid by means of the mechanism described below, constituting a modified parallel motion. The cross-head consists of an angular piece of iron of T-section, to the vertical part of which the upper pair of lazy-tongs f are attached by means of the cross-head pin g'. From this pin, the shank of which is

preferably squared, there depends a slotted plate h , with slot h' , and with this slot engages a pin h^2 , projecting from one end of an arm h^3 , the other end of which is pivoted to 5 the nearest joint f' of the lazy-tongs f . Upon the two lateral ends of the cross-head are two brackets carrying two wheels, which conveniently hold the top of the escape outward from the wall of a house. To the opposite side 10 of the cross-head are fastened the two extremities of the wire, rope, or chain ladder k , which runs downward over all the lazy-tongs, around the tension-roller c^5 , Figs. 1, 2, and 3, and is coiled onto the drum l , which is mounted 15 upon the axle of the cart-wheels, so that when the lazy-tongs are expanded the rope ladder is also drawn up and unwound from the drum l .

On one side of the drum l there is rigidly connected a smaller drum m , round which is 20 coiled a wire guide-rope m' , Figs. 2 and 3, which is led upward toward and along part of the back of the frame b , round tension pulley-wheels m^2 m^3 , and down the slot n , formed in a center bar in the frame b , Fig. 3, where it 25 is connected to a bolt-pin f^2 , with a large head, engaging with the under side of the slot n , projecting downward from the lowest cross-joint f' of the lazy-tongs f . When the lazy-tongs are projected or raised, the rope m' , ex- 30 tending from the bolt-pin f^2 to the drum m , will be wound upon said drum by the rotation of the drum l , caused by the unwinding of the rope ladder therefrom. As the lazy-tongs are collapsed or lowered the movement 35 of the pin f^2 will unwind the rope m' , causing the drum m to rotate, and with it the drum l , whereby the rope ladder will be automatically rewound upon its drum when the ladder is lowered. The connection between the lazy- 40 tongs and the frame will keep the plane of the lazy-tongs when being raised parallel with the plane of the frame b at whatever angle it is tilted.

Referring to Fig. 10, which shows a method 45 of employing longitudinal coiled springs to assist in raising the lazy-tongs, o is a barrel which is placed parallel with the center bar in frame b and is provided on one side with a slot o' , which contains a powerful coiled spring 50 o^2 . To the head of this spring is fastened in any convenient manner a wire rope o^3 , the other end of which is fastened to the lowest joint f' , where two of the lazy-tongs f meet. I also prefer in some cases to use transverse 55 springs, connecting the outside joints of the lazy-tongs, as shown in Fig. 3.

Referring now to Figs. 8 and 9, p is a four-wheeled conveyance supporting the platform and frame a and b , as previously described. 60 The frame b is, however, tilted in a different manner, the mechanism for which consists of a supplementary smaller set of lazy-tongs q , as shown, expanded and contracted by a screw q' , similar to that shown and described in 65 Fig. 1, but of reduced size.

The method of operating my improved fire-escape is as follows: The apparatus being

hauled to the spot where its services are required, it is only necessary to tilt the carriage by means of the pinion and rack c c' and turn 70 the handles e^2 c^6 , so as to draw the nut-sockets c^3 closely together, when the lazy-tongs f would be rapidly extended to any height required, carrying with them the ladder k . When extended to the necessary height, it is 75 ready for ascent or descent. When no longer required, the screw is turned the reverse way and the nut-sockets caused to recede from each other when the lazy-tongs collapse.

Having now described my invention, what 80 I claim as new, and desire to secure by Letters Patent, is—

1. In a fire-escape, the combination with the platform, of a tilting frame pivoted thereto, means connecting the platform and frame 85 to effect the adjustment of the latter, a series of lazy-tongs pivoted together and carried by said frame, a connection between said frame and tongs whereby the tongs will travel in a plane parallel with the frame, a cross-head 90 connected to the upper end of said tongs and having a lateral extension therefrom carrying friction-rollers, traveling nuts carried by the opposite end of said tongs, a right and left hand screw secured to the frame and on which 95 said nuts travel in opposite directions, and means for operating said screw, substantially as described.

2. In a fire-escape, the combination with the platform, of a tilting frame secured thereto, a series of lazy-tongs pivoted together and carried by said frame, means to move one end of said tongs in opposite directions, means for tilting said frame, and a connection between said frame and tongs whereby the tongs 105 will travel in a plane parallel with the frame, substantially as described.

3. In a fire-escape, the combination with a support, of a series of lazy-tongs pivoted together and carried upon said support, means 110 for moving one end of said tongs in opposite directions, a flexible ladder connected to said tongs, a drum on which said ladder is wound, and means operated by the movement of said tongs to rotate said drum when the tongs are 115 collapsed, substantially as described.

4. In a fire-escape, the combination with a support, of a series of lazy-tongs pivoted together and carried upon said support, means for moving one end of said lazy-tongs in opposite directions, a flexible ladder connected to the free end of said tongs so as to be carried therewith, a drum on which said ladder may be wound, an auxiliary drum connected to said first-mentioned drum, and a connection between said auxiliary drum and the lazy-tongs to rotate said drum and rewind the ladder when the tongs are collapsed, substantially as described.

5. In a fire-escape, the combination with 130 the platform of a tilting frame secured thereto, a series of lazy-tongs pivoted together and carried by said frame, means for moving one end of said tongs in opposite directions, a

- cross-head secured to the opposite end of said tongs, lateral extensions at the opposite sides of said cross-head, a flexible ladder connected to one of said extensions, and friction-rollers 5 located upon the opposite extension, substantially as described.
6. In a fire-escape, the combination with a support, of a series of lazy-tongs pivoted together and carried by said support, means for moving one end of said tongs in opposite directions, a spring located upon said support, and a connection extending from said spring to the tongs to expand the latter, substantially as described.
7. In a fire-escape, the combination with a support, of a series of lazy-tongs pivoted together and carried thereby, means for moving one end of said tongs in opposite directions, a casing secured to said support, a spring located in said casing, and means connecting said spring with the lazy-tongs, substantially as described.
8. In a fire-escape, the combination with a support, of extending lazy-tongs pivoted together, operating mechanism for extending said tongs, a slotted way connected to said support, and a standard traveling in said way, and connected to said tongs to guide the tongs in a plane parallel to said support, substantially as described.
9. In a fire-escape, the combination with the platform, of a tilting frame secured thereto, means for tilting said frame carried by said platform, a series of lazy-tongs pivoted together, a right and left hand screw secured to said frame, traveling nuts upon one end of said lazy-tongs, a cross-head upon the opposite end of said tongs, a slotted way secured to said frame, a bolt traveling in said way and connected to said tongs, a flexible ladder connected to the free end of said tongs, a drum on which said ladder may be wound, and springs connected to said tongs to assist in extending the same, substantially as described.

Signed at 97 Newgate Street, London, this 27th day of December, 1895.

FRANCIS LYST.
